FUEL FEED SYSTEM

Walter H. Weber, Detroit, Mich., assignor to
Detroit Lubricator Company, Detroit, Mich., a
corporation of Michigan

Application December 29, 1938, Serial No. 248,161

21 Claims. (Cl. 158—36.1)

My invention relates generally to internal combustion engines and more particularly to fuel feed systems therefor.

One of the objects of my invention is to provide a new and improved fuel feed system for internal combustion engines and one which is efficient in operation yet inexpensive to manufacture.

Another object of my invention is to provide a fuel feed system of the type having a container into which fuel is fed from a fuel tank for delivery to an engine and to provide for controlling flow of fuel from the fuel tank to the carburetor of the engine in a new and novel manner.

Another object of my invention is to provide a fuel feed system of the above mentioned character cooperatively connected with the engine in a manner such that a low subatmospheric pressure is obtained in the container or vacuum tank.

Another object of my invention is to provide a new and improved fuel lifting system for lifting fuel from a fuel tank to a vacuum tank for supply to an engine carburetor, and a system eliminating expensive mechanism for controlling the flow of fuel into the vacuum tank and flow therefrom to the carburetor, without sacrificing efficiency of operation of the system.

Another object of my invention is to provide means for obtaining a greater vacuum in the vacuum tank than the average vacuum which is obtained in the engine intake means.

The invention consists in the improved construction and combination of parts, to be more fully described hereinafter and the novelty of which will be particularly pointed out and distinctly claimed.

In the accompanying drawing, to be taken as a part of this specification, I have fully and clearly illustrated my invention, in which draw-

ing—
Figure 1 is a fragmentary view in side elevation of an internal combustion engine having my new and improved fuel feed system associated therewith, certain of the parts of which are in section and certain parts of which are broken away;

Fig. 2 is a detail view shown in vertical section and taken along the line 2—2 of Fig. 1;

Fig. 3 is a detail view in vertical section showing a modified form of a part of the apparatus of my invention and which may be substituted for the construction shown in Fig. 2;

Fig. 4 is a detail view in vertical section showing another modified form of a part of the appa-

ratus of my invention and which may be substituted for the structure shown in Fig. 2, and

Fig. 5 is a detail view in vertical section showing a still further modified form of a part of the apparatus of my invention and which also may be substituted for the structure shown in Fig. 2.

Referring to the drawing by characters of reference, in which like parts in the various figures are designated by like numerals, the numeral 1 designates in general an internal combustion engine the block of which has the usual intake ports 2 leading into the cylinders of the engine and controlled by valves, one of which is indicated at 3 and shown in closed position or

engaging its seat 4. Enclosing the inlet ports 15 2 there is shown a conventional type of intake manifold 5 which is bolted to the side of the engine block and to which is connected a carburetor 6. A vacuum tank or fuel container 7 is provided and into which fuel is drawn or lifted 20

from a fuel tank 8 for delivery to the carburetor 6. The fuel tank 8 has a suitable vent to atmosphere, as at 8a. Connecting the fuel tank 8 and the vacuum tank 7 there is a conduit or pipe 9 having its lower end 9a extending into and sub- 25

stantially to the bottom of tank 8 and its other end 9b secured in fluid-tight relation to an up- 30

standing tubular conduit member 10 within tank 7. The vacuum tank 7 is connected from a point adjacent the bottom thereof to a liquid receiving tank or fuel reservoir, such as a constant 35

level chamber 6a of the carburetor 6, by means of a pipe or conduit 11. The upstanding tubular member 10 projects upwardly from the bottom wall of the vacuum tank 7 and may be integral therewith, as shown. The lower or inlet end portion of the conduit 9 may be secured, as at 11a, to and extend through the top wall or cover plate of the fuel tank 8.

The tubular member 10 preferably extends to a point adjacent the top wall of vacuum tank 7 and has at its outlet end an internal transverse wall 12 through which is provided an aperture or valve port 13 that constitutes the inlet port to the vacuum tank 7. A valve member 14, which is preferably in the form of a ball and loosely disposed in the upper end of the tubular inlet member 10, is adapted to seat on the upper face of transverse wall 12 and control the port 13.

A transversely extending, valve retaining pin 15 having its opposite ends fixed in the wall of member 10 may be provided above the ball valve 14 to limit upward movement of the ball valve away

from the port 13. The ball valve 14 is readily movable by suction to open the valve port 13 to 55

permit the passage of fuel from the tank 8 into the container or vacuum tank 7, but acts upon increase of pressure in tank 7 to close port 13 to prevent flow of fuel back through conduit 9 from the tank 7.

In the bottom wall of the vacuum tank 7 there is provided an outlet aperture which is surrounded within the vacuum tank by a vertically extending tubular member 16 having a closed upper end in which is provided a centrally located aperture or valve port 17 which constitutes the outlet port of container 7. Disposed within the tubular member 16 for controlling the outlet port 17 there is an upward seating valve member 18 which, like the inlet valve member 14, is preferably a loosely disposed ball, the ball being limited in its downward movement by a transversely extending pin 19, or other suitable means, fixed to the wall of and within tubular member 16. The upper or inlet end of the conduit 11 extends into tubular member 16 and may be sealed and secured therein, such as by solder, while the outlet or lower end of the conduit 11 is, as above described, connected to the inlet of the constant level chamber 6^a of the carburetor 6 in any suitable manner.

The vacuum tank or container 7 is provided with another valve controlled port 21 which opens to atmosphere and is controlled by a valve 22, preferably a loosely disposed ball. In the present instance, the port 21 is located in a substantially horizontally extending wall portion 23 within and dividing a tubular external housing member 24 positioned vertically on the outside wall of the tank 7. The interior of housing member 24 above the wall portion 23 is in communication with the interior of the tank 7 through an aperture 25 in the side wall of the tank. The housing member 24 has a lower end portion 26 below the wall portion 23 and providing a housing for the ball valve 22, the housing portion 26 being open at its lower end to atmosphere. A pin 27, or other suitable means, may be fixed in the lower end portion 26 to limit downward movement of the ball valve 22. Projecting inwardly from the wall of container 7 and adjacent the aperture 25 is a lip or supporting portion 28 carrying a supporting or fulcrum pin 29. Pivoted on the fulcrum pin 29 is a lever member 30 having one end 31 projecting through the aperture 25 and overlying the port 21 of the wall portion 23. Within the container 7 and carried by the other end 32 of the lever member 30 is a float member 33 which acts upon predetermined rise in liquid level within the container 7 to pivot and rotate the lever 30 in a counterclockwise direction, facing Fig. 1. Upon rotation of the lever member 30 by the increased liquid level within container 7, a downward extending pin portion 34 carried by the lever end 31 moves downward through the port 21 to engage the ball valve 22 to prevent the closing of this valve until the liquid level in the container 7 has again been reduced below the predetermined level, as will be more clearly pointed out hereinafter.

In order to efficiently control the supplying of fuel from the fuel tank 8 to the carburetor 6, I connect the vacuum tank 7 to a cylinder of the engine 1 in a manner such that supply of fuel from the fuel tank to the carburetor is controlled by the operation of the intake valve 3. The vacuum tank 7 may be connected to the engine 1 by duct means, or it may be connected thereto by a conduit 40, as shown in the present instance. The conduit 40 may have one end portion sealed

and secured, such as by solder, in a tubular boss 41 formed on and surrounding an aperture through the top wall of vacuum tank 7. The other end of the conduit 40 is connected to a wall of the engine block and is in communication with a passage or bore 42 which opens through the beveled face of the valve seat 4. Thus as the valve 3 operates to alternately open and close its port, it also alternately opens and closes the opening of passageway 42 leading through the valve seat 4. By arranging the passageway 42 such that it opens through the beveled face or seat 4 of the valve port, a subatmospheric pressure is obtained in the vacuum tank 7 which is relatively lower than the pressure in either the cylinder or the manifold. The mixture in passing the end of tube or conduit 42 has the effect of an aspirator, thereby lowering the pressure in conduit 42. In this manner I make use of the restriction to flow afforded by the annular valve seat projecting into the passageway to increase the velocity of the fuel mixture passing the end of conduit 42 to increase the suction effect on the passageway or conduit 42. The annular passageway of diverging form afforded between the valve 25 face and its seat as the valve opens and closes is of less effective flow area than the flow area of the inlet port 2, and in conjunction with the flaring passageway at the valve seat provides a Venturi effect increasing the velocity of flow of the fuel mixture.

The passageway or bore 42 is angularly disposed relative to the outer side wall of the engine block and opens at its outer end into a relatively larger bore 44 which leads out of the side wall of the engine block. The bore 44 is threaded to receive a threaded end portion of a tubular connecting member 45 having its outer end threaded to receive a nut 46 for connecting one end of the conduit 40 to the connecting member 45. The conduit 40 may be formed with a flared end portion adapted to receive the outer end of the connecting member 45 which may be beveled to seat therein so that the parts may be tightly clamped together by the nut 46 to provide an air-tight connection. The volume of the space above the normal liquid level of the vacuum tank 7 should be kept as small as possible, and the length of the conduit 40 should be kept as short as possible so that a minimum of vapor or air will be extracted from the vacuum tank 7 prior to the seating of the ball valve 22 and flow of liquid from the tank 8.

The operation of my fuel lifting and supply system so far described is as follows: When the engine is operating, the intake valve 3 will alternately establish and close communication between the engine cylinder and the vacuum tank 7. Assuming that the liquid level in the vacuum tank 7 is below the predetermined level and the intake valve 3 opens, engine suction will withdraw air and vapor from the vacuum tank 7 and the resulting reduced pressure in tank 7 will cause the ball valve 22 controlling the port 21 to be lifted to its seat so that a further reduced pressure in tank 7 will result. The ball valve 18 controlling the outlet port 17 will then close and at substantially the same time the ball valve 14 controlling the inlet port 13 will be lifted from its seat so that the vacuum created in vacuum tank 7 by engine created suction and transmitted through conduit 40 causes a quantity of fuel to be drawn or lifted from the fuel tank 8 into the vacuum tank 7. When the intake valve 3 seats or closes its port, the ball valve 22 will drop by grav- 75

ity and open the port 21 to admit air to the vacuum tank 7, and the ball valve 14 will also drop onto its seat and close its port 13. Also, the ball valve 18 controlling the outlet port 17 will drop 5 and open port 17 so that fuel in the vacuum tank will flow by gravity through the conduit 10 to the carburetor 6. Thus under the control of the intake valve 3, fuel will be alternately drawn into and discharged from the vacuum tank 7 and will 10 be supplied to the carburetor 6. If desired, the vacuum tank 7 may be connected to two cylinders of the engine by an additional conduit, and with such a dual connection the lower pressure in the tank will be established twice as often. Should 15 the liquid be drawn into the tank 7 more rapidly than it flows from the tank 7 so that the liquid level therein rises beyond a predetermined point, the float member 33 will rock the lever member 30 which, by means of the portion 34 thereof, 20 will hold the ball valve 22 from seating, thereby preventing a reduction of pressure in the container 7 sufficient to cause liquid to flow from tank 8 to container 7.

Referring now to Fig. 3, this view shows 25 another manner of connecting the vacuum tank 7 with a cylinder of the engine so that communication therebetween is controlled by operation of a fuel inlet controlling valve 3^a of the cylinder similar to valve 3 of Fig. 2. In the present instance the valve 3^a has a stem 49 guided 30 in a sleeve member 50 which is integral with the engine block. The sleeve member 50 which extends upward into the fuel mixture inlet passageway, indicated at 51, is joined to the wall of 35 passageway 51 by a rib or wall portion 52 which extends transverse to the longitudinal axis of the valve stem. Opening through the outer wall of the engine block there is a bore or passageway 53 which extends transverse to the valve stem 40 and through rib 52 and sleeve member 50 and which intersects the bore of the sleeve member and opens, as at 53^a, into the fuel mixture inlet 45 passageway 51. At its outer end the bore 53 may be formed having an enlarged portion 53^b which 50 may be threaded for receiving one end of a tubular fitting or connecting member 54, to the other end of which the conduit 40 may be tightly attached by a clamping nut 55. The stem 49 of the valve 3^a functions, in this construction, as a 55 ported piston or sleeve valve and is provided with an aperture 56 extending transversely therethrough which registers with the bore 53 to establish communication between the engine cylinder and the vacuum tank 7 when the valve 3^a opens. 60 When the valve 3^a is seated, as shown, it will be seen that the valve stem closes communication between the fuel inlet passageway 51 and the vacuum tank 7. It will thus be seen that by the construction of Fig. 3, the engine created suction is intermittently applied to vacuum tank 7 by means of operation of an engine intake valve, thereby permitting, as above described, the feeding of fuel from the tank 7 to the carburetor 6. The construction shown in Fig. 3 is particularly 65 suitable for multiple cylinder engines wherein the pistons have overlapping operation, for the suction force of a plurality of cylinders may be utilized to lift fuel to the vacuum tank, the suction force being controlled by one valve. When 70 the valve 3^a is in open position, the cylinder to which the valve controls flow will be in open communication with tank 7 through intake port 51, passageway 53, valve aperture 56 and conduit 40. Also, the other cylinder whose piston operates 75 in overlapping relation with the piston of the

previously mentioned cylinder will be in open communication with tank 7 through the manifold 5, intake port 51, passageway 53, valve aperture 56 and conduit 40. It will be seen that in the construction of Fig. 3 only one connecting conduit need be employed between the engine and the tank 7 since communication between the several engine cylinders and the vacuum tank can be controlled by one valve, namely the slide valve 49. It will be evident from the foregoing 10 that the conduit 40 may be branched at its manifold end and each branch terminate at a control valve similar to the slide valve 49. In such a case the frequency with which the subatmospheric pressure is applied to the tank 7 is increased proportionally relative to the number of branches. 15

Referring now to Fig. 4, this view shows another manner of connecting the vacuum tank 7 to an engine cylinder so that fuel will alternately be drawn into the vacuum tank and delivered to the carburetor 6. In the wall of the engine block there is a passageway or bore 58 which opens into the fuel mixture inlet passageway, designated by the numeral 59, at a point 20 above or on the cylinder side of an engine inlet valve 3^b and closely adjacent thereto. In this construction the valve 3^b cooperates with the passageway 59 to form an annular space or restricted mixture flow portion. The outer end of the bore 58 opens through the outer side wall of the engine block and may have an enlarged end portion internally threaded for receiving one end of a tubular shaped fitting or connecting member 60. The outer end of the fitting 60 may also 25 be externally threaded for receiving an internally threaded end of a valve housing 61. The valve housing 61 has a longitudinal passageway or bore 62 communicating with the inlet passageway 59 through the tubular connecting member 60. The bore 62 preferably has a reduced portion 63 at its outer end providing an inwardly facing, annular shoulder forming a seat for a valve member 64. The valve member 64 which is preferably a ball is urged against its seat by 30 a coil spring 65 disposed in bore 62. One end of the conduit 40 may be connected to the outer end of the valve housing 61 by a clamping nut 66. On the suction stroke of the piston in the cylinder with which the bore 62 communicates, fuel 35 mixture will pass by the open valve 3^b to the cylinder. The valve 3^b will move on opening, substantially into or through the plane of the outlet of bore 58 and cooperates as mentioned hereinbefore to form an annular orifice passageway wherein the velocity of the fuel mixture supplied from the intake manifold 5 to the cylinder has a relatively high velocity and the pressure thereof is relatively low. It will also be noted 40 that the annular mixture stream will be directed by the flared orifice or diverging valve face into sweeping relation to the outlet of passageway 58. In this manner I obtain an increased subatmospheric pressure in the container 7, by pressure 45 reduction and aspirator action, similar to that obtained by the construction illustrated in Fig. 2. The ball valve 64 in this modification is controlled by the intake valve 3^b, due to its control of the flow of fuel mixture to the engine cylinder. Upon closing of the valve 3^b which shuts off the fuel mixture flow, the spring 65 seats the ball valve 64 thereby preventing further communication between the inlet passage 59 and the container 7 so that pressure can increase in the 50 55 60 65 70 75

container 7 to permit flow of fuel to the carburetor.

In the modification shown in Fig. 5, a tube 70 having a throat or internal restricted portion, preferably of converging-diverging form, such as a Venturi type tube, extends through the engine casting similarly to the conduit 42 of Fig. 2 and has its outlet end opening through the valve seat 4, as at 71. The inlet end 72 of the tube 70 preferably is open to atmosphere, as shown, or may be supplied with fluid from some other relatively high pressure source. The conduit 40 leading from the container 7 is suitably secured and sealed to and in open communication with the throat of the Venturi tube 70. In this construction the velocity and aspirator action of the fuel mixture is utilized as in the construction of Fig. 2, and in addition thereto the action of the Venturi tube 70 will increase still further the subatmospheric pressure on conduit 40 and within the container 7. Due to the admission or bleeding of air into the conduit 40 at the air inlet 72 of the Venturi tube 70, the gravity operated ball valve 22 controlling admission of atmospheric air to container 7 may be omitted and the increase in pressure within the container 7 be accomplished by air flowing through the end 72 of the tube 70 and conduit 40. The omitted gravity operated valve 22 may be replaced by a valve so arranged relative to the port 21 that under normal operation the valve remains against its seat, but upon the liquid within the container 7 reaching the predetermined level, the valve is operable to be moved by the float member 33 to open position. This normally closed, float member opened valve replacing the valve 22 is in the nature of a safety valve in that it assures that the suction on conduit 40 when the intake valve 3 opens will be substantially satisfied or sufficiently so that no additional liquid fuel will be pushed by the atmospheric pressure in the supply tank 8 into the container 7 so long as the liquid remains at the predetermined level.

From the foregoing description it will be seen that I have invented a new and improved means by which liquid fuel may be supplied to an internal combustion engine, and which utilizes a minimum of parts placed in an improved cooperative arrangement. By my invention a vacuum or subatmospheric pressure greater than that in the engine intake means may be obtained in a container or vacuum tank so that liquid fuel will be pushed by the supply tank pressure into the container which may be positioned considerably above the level of the supply tank. I have also disclosed means whereby an engine intake valve is utilized as the means for controlling the lowering of the container or vacuum tank pressure intermittently so that fuel can flow from the container to the carburetor. I have also disclosed a means operable upon a predetermined level of liquid in the container to prevent further liquid flow to the container. I have further disclosed a construction by which the conduit member from the vacuum tank or container may be connected to the engine to eliminate as far as possible any plugging of the conduit member due to a deposit of carbon, as was experienced in certain of the fuel lifting devices of the prior art.

This application is a continuation in part of my copending application, Serial No. 61,740, filed January 31, 1936, for Fuel feed systems.

What I claim and desire to secure by Letters Patent of the United States is:

75 1. In a fuel feeding system for an internal

combustion engine, an intake means for supplying a fuel mixture to a cylinder of the engine, a fuel tank, a fuel reservoir, means for lifting fuel from said fuel tank for delivery to said reservoir, comprising a container in communication with said fuel tank, conduit means connecting said intake means and said container to provide communication therebetween, said conduit means being so arranged and constructed relative to said intake means that flow through said intake means to the cylinder will cause a reduction of pressure in said conduit means, means synchronously controlling the supply of fuel mixture to the engine cylinder and the pressure in said container so that fuel will flow from said fuel tank into said container when the fuel mixture is being supplied to the engine, and means for supplying fuel from said container to said reservoir.

2. In a liquid lifting device, an internal combustion engine, intake means for supplying a fuel mixture to said engine comprising an intake valve, a liquid supply tank, a liquid receiving tank, conduit means connecting said tanks, conduit means connecting said receiving tank to said intake means adjacent said intake valve so that at an open position of said valve a reduced pressure is induced into said receiving tank through said last-named conduit means, at least a part of said pressure reduction being produced by the high velocity of the fuel mixture passing said valve, and conduit means leading from and for flow of liquid from said receiving tank.

3. In a fuel feeding system for an internal combustion engine having an intake means, an intake valve controlling flow of fuel mixture to a cylinder of the engine and cooperable when open with said intake means to provide a restricted flow area, and conduit means connected to said intake means adjacent said intake valve so that the fuel mixture passing through said restricted area will cause an aspirator effect on said conduit means.

4. A fuel feed system for an internal combustion engine having a port controlling valve comprising a fuel supply tank, a carburetor for the engine, a container, conduit means connecting said tank, said carburetor and said container, means providing a reduced pressure, and duct means connecting said container to said reduced pressure means and controlled by the port controlling valve, said valve when in open position establishing communication between said reduced pressure means and said container to decrease the fluid pressure therein so that fuel will be discharged into said container from said fuel supply tank for flow through said conduit means to said carburetor, said valve when in closed position closing communication between said reduced pressure means and said container.

5. A fuel feed system for an internal combustion engine having intake valves comprising a fuel supply tank, means operable to provide a reduced pressure, a carburetor for the engine, a container, conduit means connecting said tank said carburetor and said container, a conduit connecting said container to said reduced pressure means and having a port, an intake valve of the engine controlling said port, said intake valve when in an open position establishing communication between said reduced pressure means and said container to produce a reduced pressure in said container so that fuel will flow from said supply tank into said container, said intake valve when in closed position closing communication

5 between said container and said reduced pressure means, and valve means in the fuel conveying portion of said conduit means and controlling flow therethrough and controlled by said engine intake valve.

6. A fuel feed system for an internal combustion engine having intake and exhaust valves comprising a carburetor for the engine, a fuel supply tank disposed below the level of the carburetor, a container, conduit means connecting said container and said carburetor, conduit means connecting said container and a cylinder of the engine and having a port opening through a valve seat of one of the engine intake valves, said one valve when open establishing communication between the engine cylinder and said container to create in said container a pressure lower than the pressure in said tank so that fuel will flow from said supply tank to said container for flow therefrom to said carburetor, a valve controlling flow of fuel from said container to said carburetor, and a valve controlling admission of air to said container and controlling said fuel control valve, said one engine intake valve controlling the operation of said air control valve.

7. A fuel feed system for an internal combustion engine having intake and exhaust valves, a carburetor for the engine, a fuel supply tank, a vacuum tank between said fuel tank and said carburetor, conduit means connecting said supply tank said vacuum tank and said carburetor, duct means connecting said vacuum tank and a cylinder of the engine so that fuel will be drawn into the vacuum tank by engine created suction, one of the valves of the engine controlling communication between said cylinder and said vacuum tank and operable to close communication therebetween during exhaust of the products of combustion from the cylinder, said vacuum tank having an outlet port leading to said conduit means connecting said vacuum tank to said carburetor for flow of fuel to said carburetor, a valve controlling said outlet port and controlled by operation of said one valve to alternately open and close said outlet port, said vacuum tank having a port opening to atmosphere, and a valve member controlling said port and controlled by the operation of said one valve to alternately open and close said port to atmosphere.

8. In a fuel feed system for an internal combustion engine having a cylinder and an intake valve therefor, means for lifting fuel from a fuel tank for flow by gravity to the engine comprising a container connected to said fuel tank and into which a quantity of fuel is intermittently drawn by the intermittent production of a partial vacuum therein, duct means for transmitting the vacuum of the engine cylinder to said container, said duct means having a port opening through the seat of the intake valve so that the opening and closing of said valve controls the intermittent flow of fuel to said container.

9. A fuel feed system for an internal combustion engine having an intake valve comprising a carburetor for the engine, a fuel supply tank, a vacuum tank, said conduit means connecting said vacuum tank said fuel tank and said carburetor, means connecting said vacuum tank to a cylinder of the engine to produce a vacuum in said vacuum tank so that the greater pressure in said supply tank will push fuel into said vacuum tank from said supply tank, the engine intake valve controlling communication between said vacuum tank and said cylinder to establish communication between said vacuum tank and said cylinder upon opening of said intake valve and to close

communication between said vacuum tank and said cylinder upon seating of said intake valve, said vacuum tank having a port open to atmosphere, and a valve controlling said port and controlled by operation of said intake valve to alternately open and close said port to control flow of fuel to said carburetor.

10. A fuel feed system for an internal combustion engine having an intake valve comprising a carburetor for the engine, a fuel tank, a fuel supply line connecting said fuel tank and said carburetor, a vacuum tank in said supply line between said fuel tank and said carburetor, said vacuum tank having an inlet port, an outlet port and a port opening to atmosphere, a conduit connecting said vacuum tank to a cylinder of the engine and communicating with said cylinder through an opening in the seat of the intake valve so that when the intake valve is seated communication between said cylinder and said vacuum tank is closed, a valve controlling said inlet port and controlled by the operation of the intake valve to alternately open and close said inlet port, a valve controlling said outlet port and controlled by the operation of the intake valve to alternately open and close said outlet port, and a valve controlling said port opening to atmosphere and controlled by the operation of the intake valve to alternately open and close said port opening to atmosphere.

11. In a liquid lifting apparatus, an inlet conduit member for supplying a cylinder and having a valve port, a valve member controlling said port and open during decreased cylinder pressure, a container for liquid having an inlet and an outlet, conduit means communicatively connecting said conduit member and said container, a valve member controlling flow through said conduit means, means mechanically connecting said valve members together for simultaneous opening movement, and valve means controlling said inlet and said outlet and operable to close said outlet and to open said inlet upon opening movement of said valve members so that the decreased cylinder pressure will establish a decreased pressure in said container.

12. In a liquid lifting apparatus, an internal combustion engine, intake means to said engine, an intake valve controlling flow through said intake means and having a stem portion, a sleeve holding and guiding said stem portion, a passageway from said intake means through said stem portion and said holding sleeve, said passageway being open for flow of fluid at one position of said intake valve, a liquid supply tank having therein a higher pressure than that in said intake means, a liquid container at a level higher than that of the bottom of said supply tank, conduit means connecting said tank to said container, and conduit means connecting said passageway and said container so that the lesser pressure in said intake means will be communicated to said container thereby permitting liquid flow from said tank to said container.

13. In a liquid lifting apparatus, an internal combustion engine, intake means to said engine, an intake valve controlling flow through said intake means and having a stem portion, a sleeve holding and guiding said stem portion, a passageway from said intake means through said stem portion and said holding sleeve, said passageway being open for flow of fluid at one position of said intake valve, a liquid supply tank at atmospheric pressure, a liquid container at a level higher than that of the bottom of said supply tank, conduit means connecting said tank to said con-

- tainer, conduit means connecting said passage-way and said container so that the subatmospheric pressure in said intake means will be communicated to said container so that liquid can flow from said tank to said container, and means controlled by said valve and controlling flow of liquid from said container.
14. In a fuel feeding system for an internal combustion engine having intake means, an intake valve having an open and a closed position, a fuel supply tank open to atmospheric pressure, a container, a carburetor for supplying fuel mixture to said intake means, conduit means connecting said tank, said container and said carburetor for flow of liquid fuel, conduit means connecting said container to said intake means adjacent the top portion of said valve so that when said intake valve is in said open position said last-named conduit means opens into said intake means at the point of greatest velocity of fuel mixture flow to establish a subatmospheric pressure in said container so that liquid fuel in said tank will flow to said container, and means operable upon movement of said valve to said closed position to allow gravity flow of liquid fuel from said container to said carburetor.
15. In a fuel feed system for an internal combustion engine, an intake means for supplying a fuel mixture to a cylinder of the engine, a carburetor discharging into said intake means, a fuel tank, means for lifting fuel from said fuel tank for delivery to said carburetor comprising a container in communication with said fuel tank, duct means having one end connected to said intake means and its other end connected to said container to provide communication therebetween, said one end being so positioned relative to flow through said intake means that the flow through said intake means will induce a reduction of pressure in said one end, valve means controlling said duct means and said intake means so that subatmospheric pressure produced by engine created suction is transmitted to said container when said intake means is supplying fuel mixture to the cylinder so that fuel will flow from said fuel tank into said container, said container having an opening for admitting pressure thereinto, and valve means cooperating with and separate from and movable subsequent to movement of said first-named valve means and operable to permit flow through said opening when said first-named valve means is in closed position so that fuel can flow from said container to said carburetor.
16. A liquid fuel system for an internal combustion engine comprising intake means for connection to an engine cylinder, an intake valve, a main liquid fuel tank open to atmosphere, an intermediate fuel container, a carburetor supplying a fuel-air mixture to said intake means, conduit means connecting said fuel tank at a point adjacent the bottom thereof to said fuel container adjacent the top thereof, valve means in the container end of and controlling said conduit means to allow flow of liquid fuel in a direction solely from said tank to said container, conduit means connecting said container at a point adjacent the bottom thereof to said carburetor, valve means in said second-named conduit means and within said container and operable to allow flow of fuel in a direction solely from said container to said carburetor, conduit means having one end thereof connected to said container at a point adjacent the top thereof and having its other end connected to said intake means, said other end of said last-named conduit being so positioned relative to the flow through said intake means that the velocity of flow will induce a reduction in pressure in said last-named conduit other end, valve means controlling said third-named conduit means and said intake means so that subatmospheric pressure in said intake means is transmitted to said container so that liquid fuel can flow from said tank through said first-named conduit means to said container at one position of said controlling valve means, means controlled by said controlling valve means so that at another position of said controlling valve means a pressure increase is established in said container so that liquid fuel can flow through said second-named conduit means to said carburetor.
17. In a fuel feed system for an internal combustion engine, an intake means for supplying fuel mixture to a cylinder of the engine and having a port, an intake valve controlling said intake means, a fuel tank, means for lifting fuel from said tank for delivery to the engine comprising a container in communication with said tank, said intake valve controlling said port, duct means connecting said container to said intake means adjacent said intake valve to provide communication therebetween, said intake valve at one position acting to establish flow through said duct means so that a vacuum due to flow of fuel mixture to the engine will be produced in said container, the higher fluid pressure in the fuel tank forcing fuel into said container upon the attainment of said vacuum in said container, and means operable to relieve the vacuum in said container at another position of said intake valve.
18. A liquid lifting apparatus for use with an internal combustion engine comprising intake means leading to an engine cylinder, intake valve means in and controlling flow of fluid through said means, a storage tank open to atmosphere, a liquid container, conduit means extending from a point within and adjacent the bottom of said tank to a point within and adjacent the top of said container, conduit means connecting said container at a point substantially at the top thereof to a portion of the engine intake means at a point of restricted fuel mixture flow and adjacent said intake valve means so that an aspirator effect is produced on said second-named conduit means, valve means in and controlling said second-named conduit means so that at one position of the engine piston the subatmospheric pressure in said intake means may be communicated to said container, valve means in said first-named conduit means and controlled by said second-named valve means to oppose flow of fluid from the container, an outlet valve means from said container, valve means in said outlet means and controlled by said second-named valve means to oppose flow of fluid into said container, and means independent of said second-named valve means and operable to establish an increase of pressure in said container upon closure of said second-named conduit valve means.
19. A liquid fuel system for an internal combustion engine comprising intake means for connection to an engine cylinder, an intake valve, a main liquid fuel tank open to atmosphere, an intermediate fuel container, a carburetor for supplying a fuel-air mixture to the intake means, conduit means connecting said fuel tank at a point adjacent the bottom thereof to said fuel container adjacent the top thereof, valve means in the container end of and controlling said conduit means to allow flow of liquid fuel in a direction solely from said tank to said container, con-

duit means connecting said container at a point adjacent the bottom thereof to said carburetor, valve means in said second-named conduit means and within said container and operable to allow flow of fuel in a direction solely from said container to said carburetor, conduit means connecting said container at a point adjacent the top thereof to said intake means at a point of restricted fuel mixture flow and adjacent said intake valve means so that an aspirator effect is produced on said second-named conduit means, controlling valve means in said third-named conduit means and operable at one position of said intake valve to transmit the subatmospheric pressure in said intake means to said container so that liquid fuel can flow from said tank through said first-named conduit means to said container, said container having an air inlet opening to atmosphere, valve means mechanically independent of and controlled by said controlling valve means and controlling said opening so that at another position of said controlling valve means a pressure increase is established in said container, said pressure increase in said container permitting liquid fuel to flow through said second-named conduit means to said carburetor.

20. In a liquid lifting apparatus for use with an internal combustion engine, intake means including a valve seat, an intake valve member in said means cooperable with said valve seat, a converging-diverging member having its outlet end opening through said seat so that flow of fluid therethrough is controlled by said valve member, said second-named member having its other or inlet end open to a source of fluid supply, a liquid supply tank, a liquid containing tank, a liquid receiving tank, conduit means connecting said

tanks for flow of liquid from said supply tank through said containing tank to said receiving tank, and a conduit member connecting said containing tank to said second-named member adjacent the throat thereof so that when the fluid is passing through said second-named member to said intake means a lower pressure is maintained in said containing tank than in said supply tank so that liquid will flow from said supply to said containing tank.

21. In a liquid lifting apparatus for use with an internal combustion engine, intake means including a valve seat, an intake valve member in said means cooperable with said valve seat, a converging-diverging member having its outlet end opening through said seat so that flow of fluid therethrough is controlled by said valve member, said second-named member having its other or inlet end open to a source of fluid supply, a liquid supply tank, a liquid containing tank, a liquid receiving tank, conduit means connecting said tanks for flow of liquid from said supply tank through said containing tank to said receiving tank, a conduit member connecting said containing tank to said second-named member adjacent the throat thereof so that when the fluid is passing through said second-named member to said intake means a lower pressure is maintained in said containing tank than in said supply tank so that liquid will flow from said supply to said containing tank, and means operable upon a predetermined level of liquid in said containing tank to render said second-named member ineffective to lower the pressure in said containing tank sufficiently to cause liquid flow from said supply tank to said containing tank.

WALTER H. WEBER.
